UNITED STATES PATENT OFFICE.

LOUIS L. DRIGGS, OF NEW YORK, N. Y.

AUTO-LIMBER.

1,230,687.

Specification of Letters Patent. Patented June 19, 1917.

Application filed July 26, 1916. Serial No. 111,515.

To all whom it may concern:

Be it known that I, LOUIS L. DRIGGS, a citizen of the United States, residing at New York, in the county of New York and State 5 of New York, have invented certain new and useful Improvements in Auto-Limbers; and I do hereby declare the following to be a full, clear, and exact description of the invention, such as will enable others skilled 10 in the art to which it appertains to make and use the same.

My present invention relates to automobile limbers for use with field artillery, and has for its general object to provide means 15 for placing a gun in battery, and for discharging on the ground in the rear of the gun, the ammunition therefor, without exposing the gun's crew to the enemy's fire.

My invention will be understood by reference to the accompanying drawings, in which similar reference symbols indicate similar parts throughout the several views,— and in which:

Figure 1 is a side elevation of the auto-limber showing the muzzle of the gun broken away.

Fig. 2 is a top plan view of a portion of the auto-limber with parts broken away, to show the parts beneath.

Fig. 3 is a longitudinal sectional view of that portion of the auto-limber shown in Fig. 2, but showing the door in different positions, and showing the shelf tilted in dotted lines.

Fig. 4 is a rear elevation of a portion of the auto-limber with parts broken away; and

Fig. 5 is a detail perspective view of one of the ejectors and its guide bars.

The auto-limber consists of a chassis 1 upon which is built up an armor plate enclosure 2 for housing the men, engine and ammunition.

The gun carriage 3 is hooked to the rear 45 of the limber, and means are provided whereby the carriage may be released from the limber by an operator in the cab.

When the gun has been placed in the desired position the chauffeur by means of 50 the foot pedal 4, located in the cab, releases the trail of the gun carriage from a hook 5 (see Fig. 3) located at the rear of the limber. The pedal is connected by means of a rod 6 to a trigger 7, in the form of a bell crank, which is pivotally mounted on a

shaft 8 journaled in bearings 8^a mounted on the chassis adjacent the rear end thereof.

The outer end of the bell crank is forked and is arranged so as to engage the trail of the gun at each side of the hook, as shown 60 in Fig. 3, so that when the pedal is pushed to its forward position, the bell crank is rocked lifting the eye 3^a of the trail from the hook 5, and as the auto-limber is started forward the trail, being released from the 65 hook, drops to the ground. After the auto-limber has been moved the desired distance from the gun it is stopped, and the operation of discharging the ammunition then proceeds.

The ammunition is housed within an armor plate chest 9 located on the rear of the chassis frame. A door 10 hinged as at 70 10' to the chassis frame is provided for closing the rear of the chest. This door 75 has a flap 10^a hinged to its upper end adapted to swing over the rear upper portion of the ammunition chest, and form a partial cover for same. The door 10 and flap 10^a are provided with suitable reinforcing ribs 80 10^b and 10^c; and hinged to the door are the side props 11 to form supporting parts for the door and flap when the same are in the lowered position shown in dotted lines in Fig. 3.

The door 10 is arranged to be opened by an operator within the cab, as will now be described. Located within convenient reach of the operator is an operating handle 12, which through sprocket and chain connection 13, rotates a shaft 14 upon which are mounted two pulleys, 15, (see Fig. 2). Over these pulleys are wound cables 16 which are carried rearwardly, are trained over sheaves 17 mounted on the rear outer sides of the 90 ammunition chest, and are connected to the door 10 at each side thereof. A ratchet and pawl connection as indicated at 18 normally prevents the turning of the shaft except in one direction.

The ammunition boxes 20 are preferably arranged in two tiers. I have shown three boxes in each tier; and it is desired to eject the lower tier first and then the upper tier as will now be described.

The bottom plate 9^a of the ammunition chest is provided with a series of antifriction rollers 21 adapted to engage and support the bottoms of the ammunition boxes 20, between which rollers I provide guide 110

boxes 22, preferably with overhanging flanges 22^a adapted to engage the flanges 23^a of the ejectors 23. These ejectors are attached to ropes or chains 24 passing over pulleys 24^a and beneath pulleys 25 (see Fig. 2) terminating in handles 24^b (see Figs. 2 and 5) so that pulling up on any one of these handles 24^b will press forward the corresponding box of ammunition resting 10 on the antifriction rollers 21.

The second tier of ammunition boxes is mounted on a shelf 26 hinged on the rock shaft 27 in the ammunition chest, and having its forward end supported by the props 28, which props are connected by the links 31 and the arms 30, fast to the rock shaft 27, to which rock shaft, the handle 29 is also rigidly attached. If the handle 29 is moved from the position shown in full lines 15 to the position shown in dotted lines in Fig. 3, the props 28 will be withdrawn from beneath the ammunition boxes, and the shelf 26 will be tilted down to the position shown in dotted lines in Fig. 3.

25 A suitable seat 40 (see Fig. 3) is provided for the chauffeur, and crew.

The operation of the device is as follows:

The parts being in position shown in Fig. 1 the automobile is stopped and pedal 4 is pushed down releasing the hook 5 from engagement with the trail of the gun, and when the automobile is started forward, the trail will drop to the ground and the gun will be in battery. After the automobile 20 has proceeded to a short distance to the rear, it is stopped and the hand crank 12 is rotated until the door 10 falls to the position shown in full lines in Fig. 3, at which times the props 11 will rest on the ground, and will support the door in a substantially horizontal position.

45 Now by operating the ejectors 23 by means of the handles 26, the ammunition boxes are forced out on to the door 10. When the desired number of these have been ejected, a slight forward movement of the automobile will cause the props 11 to swing from beneath the support of the door 10, and the door 10 and flap 10^a will swing to the position shown in dotted lines in Fig. 3 and the ammunition boxes will slide to the ground.

Now if the automobile be moved forward again a slight distance and the handle 29 be turned from the position shown in full lines to the position shown in dotted lines in Fig. 3, the shelf 26 will swing down to the position shown in dotted lines in Fig. 3, and will form a slide way for the ammunition boxes on said shelf, all of which boxes 55 will slide down said shelf, door 10, and flap 10^a to the ground, and will be readily available for the gun's crew.

60 It will be noted that the props 11 hinged to door 10 will serve as supporting rails to the door 10, and the flap 10^a when the

same are in the lowered position shown in dotted lines in Fig. 3.

Should it be desired to return any of the unused ammunition boxes to the limber, the door may be returned to the position shown 70 in full lines in Fig. 3, and the ammunition boxes replaced on either the shelf 26 or the chamber beneath same, and the door may be swung back to the closed position, the parts being returned to the initial position.

75 The ammunition door is closed by simply turning the hand crank 12 in the reverse direction. Thus it will be seen that the ammunition boxes on the lower tier may be ejected and dumped singly or they may all 80 three be ejected and dumped simultaneously, while the ammunition boxes on the upper tier may be all dumped at one operation.

85 During movement from place to place the gun's crew are carried in the cab and protected from small-arm fire by the armor thereof, and the gun may be readily thrown into action and the ammunition promptly supplied to the rear thereof as herein described.

90 It will be obvious that various modifications might be made in the herein described apparatus and in the construction, combination and arrangement of parts which could be used without departing from the spirit 95 of my invention.

Having thus described my invention, what I claim and desire to secure by Letters Patent of the United States is:

1. In an auto-limber, the combination with 100 a chassis and an armored body carried thereby, of an ammunition chest carried by said armored body, a hinged door normally closing one end of said ammunition chest, said door being adapted when in the lowered 105 position to form a slideway for the ammunition boxes, and means operable from the interior of said armored body for raising and lowering said door, substantially as described.

2. In an auto-limber, the combination with 110 a chassis and an armored body carried thereby, of an ammunition chest carried by said armored body, a hinged door normally closing one end of said ammunition chest, 115 props hinged to the sides of said door, said props serving as supports for said door when in the lowered position, and means operable from the interior of said armored body for raising and lowering said door, substantially as described.

3. In an auto-limber, the combination with a chassis, and a platform mounted thereon, of an ammunition chest carried by said platform at the rear end thereof, a hinged door 125 normally closing the rear end of said ammunition chest, a flap hinged to the upper end of said door, and adapted to close part of the top of said chest, props hinged to the sides of said door, said props serving as 130

- supports for said door, when lowered to the substantially horizontal position, and also as supports for said door and flap when in the lowered position, said door and flap being adapted when in the lowered position to form a slideway for the ammunition boxes, with means for raising and lowering said door, substantially as described.
4. In an auto-limber, the combination with a chassis and a platform mounted thereon, of an ammunition chest carried by said platform at the rear end thereof, antifriction rollers mounted in the base of said ammunition chest, and supporting the ammunition boxes resting thereon, means operable from the interior of the limber for pushing said ammunition boxes rearward in said chest, a hinged door normally closing the rear end of said ammunition chest, said door being adapted when in the lowered position to form a slideway for the ammunition boxes with means for raising and lowering said door, substantially as described.
5. In an auto-limber, the combination with a chassis, and a platform mounted thereon, of an ammunition chest carried by said platform at the rear end thereof, antifriction rollers mounted in the base of said ammunition chest, and supporting the ammunition boxes resting thereon, means operable from the interior of the limber for pushing said ammunition boxes rearward in said chest, a hinged door normally closing the rear end of said ammunition chest, a flap hinged to the upper end of said door, and adapted to close part of the top of said chest, props hinged to the sides of said door, said props serving as supports for said door, when lowered to the substantially horizontal position, and also as supports for said door and flap when in the lowered position, said door and flap being adapted when in the lowered position to form a slideway for the ammunition boxes, with means for raising and lowering said door, substantially as described.
6. In an auto-limber, the combination with a chassis and an armored body carried thereby, of an ammunition chest carried by said armored body, a hinged shelf mounted in said ammunition chest and dividing the same into an upper and a lower compartment for the storage of ammunition boxes, means for tilting said shelf when desired, a hinged door normally closing one end of said ammunition chest, said door being adapted when in the lowered position to form a slideway for the ammunition boxes, and means operable from the interior of said armored body for raising and lowering said door, substantially as described.
7. In an auto-limber, the combination with a chassis and an armored body carried thereby, of an ammunition chest carried by said armored body, a hinged shelf mounted in said ammunition chest and dividing the same into an upper and a lower compartment for the storage of ammunition boxes, means for tilting said shelf when desired, a hinged door normally closing one end of said ammunition chest, props hinged to the sides of said door, said props serving as supports for said door when in the lowered position, and means operable from the interior of said armored body for raising and lowering said door, substantially as described.
8. In an auto-limber, the combination with a chassis, and a platform mounted thereon, of an ammunition chest carried by said platform at the rear end thereof, a hinged shelf mounted in said ammunition chest and dividing the same into an upper and a lower compartment for the storage of ammunition boxes, means for tilting said shelf when desired, and a hinged door normally closing the rear end of said ammunition chest, said door being adapted when in the lowered position to form a slideway for the ammunition boxes, with means for raising and lowering said door, substantially as described.
9. In an auto-limber, the combination with a chassis, and a platform mounted thereon, of an ammunition chest carried by said platform at the rear end thereof, a hinged shelf mounted in said ammunition chest and dividing the same into an upper and a lower compartment for the storage of ammunition boxes, means for tilting said shelf when desired, a hinged door normally closing the rear end of said ammunition chest, a flap hinged to the upper end of said door, and adapted to close part of the top of said chest, props hinged to the sides of said door, said props serving as supports for said door, when lowered to the substantially horizontal position, and also as supports for said door and flap when in the lowered position, said door and flap being adapted when in the lowered position to form a slideway for the ammunition boxes, with means for raising and lowering said door, substantially as described.
10. In an auto-limber, the combination with a chassis and a platform mounted thereon, of an ammunition chest carried by said platform at the rear end thereof, a hinged shelf mounted in said ammunition chest and dividing the same into an upper and a lower compartment for the storage of ammunition boxes, means for tilting said shelf when desired, antifriction rollers mounted in the base of said ammunition chest, and supporting the ammunition boxes resting thereon, means operable from the interior of the limber for pushing said ammunition boxes rearward in said chest, a hinged door normally closing the rear end of said ammunition chest, said door being

adapted when in the lowered position to form a slideway for the ammunition boxes with means for raising and lowering said door, substantially as described.

5 11. In an auto-limber, the combination
with a chassis, and a platform mounted
thereon, of an ammunition chest carried by
said platform at the rear end thereof, a
hinged shelf mounted in said ammunition
10 chest and dividing the same into an upper
and a lower compartment for the storage of
ammunition boxes, means for tilting said
shelf when desired, antifriction rollers
mounted in the base of said ammunition
15 chest, and supporting the ammunition boxes
resting thereon, means operable from the
interior of the limber for pushing said am-
munition boxes rearward in said chest, a
hinged door normally closing the rear end
20 of said ammunition chest, a flap hinged to
the upper end of said door, and adapted to
close part of the top of said chest, props
hinged to the sides of said door, said props
serving as supports for said door, when
25 lowered to the substantially horizontal posi-
tion, and also as supports for said door and
flap when in the lowered position, said door
and flap being adapted when in the lowered
position to form a slideway for the ammu-
nition boxes, with means for raising and
30 lowering said door, substantially as de-
scribed.

35 12. In an auto-limber, the combination with a chassis and an armored body carried thereby, of means for attaching the trail of a gun to the rear thereof, and means operable from the interior of the limber for releasing said attaching means, an ammunition chest carried by said armored body, a
40 hinged door normally closing one end of said ammunition chest, said door being adapted when in the lowered position to form a slidway for the ammunition boxes, and means operable from the interior of
45 said armored body for raising and lowering said door, substantially as described.

13. In an auto-limber, the combination with a chassis and an armored body carried thereby, of means for attaching the trail of a gun to the rear thereof, and means operable from the interior of the limber for releasing said attaching means, an ammunition chest carried by said armored body, a hinged door normally closing one end of said ammunition chest, props hinged to the sides of said door, said props serving as supports for said door when in the lowered position, and means operable from the interior of said armored body for raising and lowering said door, substantially as described.

14. In an auto-limber, the combination with a chassis, and a platform mounted thereon, of means for attaching the trail of a gun to the rear thereof, and means oper-

able from the interior of the limber for releasing said attaching means, an ammunition chest carried by said platform at the rear end thereof, a hinged door normally closing the rear end of said ammunition chest, said door being adapted when in the lowered position to form a slideway for the ammunition boxes with means for raising and lowering said door, substantially as described. 70 75

15. In an auto-limber, the combination with a chassis, and a platform mounted thereon, of means for attaching the trail of a gun to the rear thereof, and means operable from the interior of the limber for releasing said attaching means, an ammunition chest carried by said platform at the rear end thereof, a hinged door normally closing the rear end of said ammunition chest, a flap hinged to the upper end of said door, and adapted to close part of the top of said chest, props hinged to the sides of the door, said props serving as supports for said door, when lowered to the substantially horizontal position, and also as supports for said door and flap when in the lowered position, said door and flap being adapted when in the lowered position to form a slideway for the ammunition boxes, with means for raising and lowering said door, substantially as described. 95

16. In an auto-limber, the combination with a chassis and a platform mounted thereon, of means for attaching the trail of a gun to the rear thereof, and means operable from the interior of the limber for releasing said attaching means, an ammunition chest carried by said platform at the rear end thereof, antifriction rollers mounted in the base of said ammunition chest, and supporting the ammunition boxes resting thereon, means operable from the interior of the limber for pushing said ammunition boxes rearward in said chest, a hinged door normally closing the rear end of said ammunition chest, said door being adapted when in the lowered position to form a slideway for the ammunition boxes with means for raising and lowering said door, substantially as described. 100 105 110 115

17. In an auto-limber, the combination with a chassis, and a platform mounted thereon, of means for attaching the trail of a gun to the rear thereof, and means operable from the interior of the limber for releasing said attaching means, an ammunition chest carried by said platform at the rear end thereof, anti-friction rollers mounted in the base of said ammunition chest, and supporting the ammunition boxes resting thereon, means operable from the interior of the limber for pushing said ammunition boxes rearward in said chest, a hinged door normally closing the rear end of said ammunition chest, a flap hinged to the upper 130

end of said door; and adapted to close part of the top of said chest, props hinged to the sides of said door, said props serving as supports for said door, when lowered to the substantially horizontal position, and also as supports for said door and flap when in the lowered position, said door and flap being adapted when in the lowered position to form a slideway for the ammunition boxes, 10 with means for raising and lowering said door, substantially as described.

18. In an auto-limber, the combination with a chassis and an armored body carried thereby, of means for attaching the trail of a gun to the rear thereof, and means operable from the interior of the limber for releasing said attaching means, an ammunition chest carried by said armored body, a hinged shelf mounted in said ammunition chest and dividing the same into an upper and a lower compartment for the storage of ammunition boxes, means for tilting said shelf when desired, a hinged door normally closing one end of said ammunition chest, 20 said door being adapted when in the lowered position to form a slideway for the ammunition boxes, and means operable from the interior of said armored body for raising and lowering said door, substantially as described.

19. In an auto-limber, the combination with a chassis and an armored body carried thereby, of means for attaching the trail of a gun to the rear thereof, and means operable from the interior of the limber for releasing said attaching means, an ammunition chest carried by said armored body, a hinged shelf mounted in said ammunition chest and dividing the same into an upper and a lower compartment for the storage of ammunition boxes, means for tilting said shelf when desired, a hinged door normally closing one end of said ammunition chest, 30 props hinged to the sides of said door, said props serving as supports for said door when in the lowered position, and means operable from the interior of said armored body for raising and lowering said door, substantially as described.

20. In an auto-limber, the combination with a chassis, and a platform mounted thereon, of means for attaching the trail of a gun to the rear thereof, and means operable from the interior of the limber for releasing said attaching means, an ammunition chest carried by said platform at the rear end thereof, a hinged shelf mounted in said ammunition chest and dividing the same into an upper and a lower compartment for the storage of ammunition boxes, means for tilting said shelf when desired, a hinged door normally closing the rear end of said ammunition chest, said door being adapted when in the lowered position to form a slideway for the ammunition boxes, 40 with means for raising and lowering said door, substantially as described.

with means for raising and lowering said door, substantially as described.

21. In an auto-limber, the combination with a chassis, and a platform mounted thereon, of means for attaching the trail of a gun to the rear thereof, and means operable from the interior of the limber for releasing said attaching means, an ammunition chest carried by said platform at the rear end thereof, a hinged shelf mounted in said ammunition chest and dividing the same into an upper and a lower compartment for the storage of ammunition boxes, means for tilting said shelf when desired, a hinged door normally closing the rear end of said ammunition chest, a flap hinged to the upper end of said door, and adapted to close part of the top of said chest, props hinged to the sides of said door, said props serving as supports for said door, when lowered to the substantially horizontal position, and also as supports for said door and flap when in the lowered position, said door and flap being adapted when in the lowered position to form a slideway for the ammunition boxes, 50 with means for raising and lowering said door, substantially as described.

22. In an auto-limber, the combination with a chassis, and a platform mounted thereon, of means for attaching the trail of a gun to the rear thereof, and means operable from the interior of the limber for releasing said attaching means, an ammunition chest carried by said platform at the rear end thereof, a hinged shelf mounted in said ammunition chest and dividing the same into an upper and a lower compartment for the storage of ammunition boxes, means for tilting said shelf when desired, 55 antifriction rollers mounted in the base of said ammunition chest, and supporting the ammunition boxes resting thereon, means operable from the interior of the limber for pushing said ammunition boxes rearward in said chest, a hinged door normally closing the rear end of said ammunition chest, said door being adapted when in the lowered position to form a slideway for the ammunition boxes with means for raising and lowering said door, substantially as described.

23. In an auto-limber, the combination with a chassis, and a platform mounted thereon, of means for attaching the trail of a gun to the rear thereof, and means operable from the interior of the limber for releasing said attaching means, an ammunition chest carried by said platform at the rear end thereof, a hinged shelf mounted in said ammunition chest and dividing the same into an upper and a lower compartment for the storage of ammunition boxes, means for tilting said shelf when desired, 60 antifriction rollers mounted in the base of

130

said ammunition chest, and supporting the ammunition boxes resting thereon, means
operative from the interior of the limber for
pushing said ammunition boxes rearward
5 in said chest, a hinged door normally closing
the rear end of said ammunition chest,
a flap hinged to the upper end of said door,
and adapted to close part of the top of said
chest, props hinged to the sides of said door,
10 said props serving as supports for said door,
when lowered to the substantially horizontal

position, and also as supports for said door
and flap when in the lowered position,
said door and flap being adapted when in
the lowered position to form a slideway for
the ammunition boxes, with means for rais-
ing and lowering said door, substantially
as described.

In testimony whereof, I affix my signature.

LOUIS L. DRIGGS.
